UNITED STATES PATENT OFFICE

2,533,597

MASTER BUSHING FOR ROTARY OIL WELL DRILLING MACHINES

August R. Maier, Oil City, Pa., assignor to Oil Well Supply Company, a corporation of New Jersey

Application March 4, 1947, Serial No. 732,166

4 Claims. (Cl. 255—23)

1

This invention relates to an improved construction and arrangement of a master bushing for rotary oil well drilling rig in which the component parts are hingedly connected yet provided with interlocking portions opposite the hinge pintle capable of being disconnected upon shifting one of the complementary portions of the bushing relative to the other, in the direction of the length of the pintle, whereupon the parts can be opened by pivoting them about the hinge pintle.

For a more complete understanding of the invention reference should be made to the following detailed description, the accompanying drawings and the appended claims.

In the drawings:

Figure 1 is a plan view of the rotary of a somewhat conventional type of oil well drilling rig showing the same equipped with the master bushing of my invention;

Figure 2 is a section on line II—II of Figure 1 showing the hinge pintle and related parts of the improved bushing in elevation;

Figure 3 is a fragmentary section through the rotary of a drilling rig with the improved master bushing in place and showing in elevation the interlocking portions thereof, the drill pipe and the usual slips being omitted in the interest of clearness;

Figure 4 is a view of the bushing in the process of being lifted from the rotary by means effective to shift one of the parts in a longitudinal direction relatively to the other so as to unlock and separate them;

Figure 5 is a plan view of the bushing showing the sections thereof swung to open position;

Figure 6 is a fragmentary detail illustrating a modification of the interlocking teeth wherein the abutting faces are tapered so as to wedgingly secure the coacting parts of the bushing;

Figure 7 is an enlarged plan view of the bushing illustrating a modified form wherein dowel pins are used for detachably interlocking the parts; and

Figure 8 is a vertical section on line VIII—VIII of Figure 7 illustrating the detail of a hinge pin having different portions which increase in size by small increments so as to facilitate the separation of the parts and also illustrating the dowel pins for effecting the interlock.

Referring in detail to the drawings, 10 represents the housing of a conventional form of rotary oil well drilling rig and 12 a power shaft for driving a bevel pinion 14 meshing with a bevel ring gear in a conventional manner so as

to rotate the table 18 of the rotary which is supported on suitable anti-friction bearings 20 as suggested in Figure 3. The rotary table 18 is provided with an approximately square aperture 22 into which is usually fitted a master bushing. The master bushing of my invention is indicated as a whole at 24 and is designed to fit the standard aperture 22 of the rotary table of a conventional drilling rig.

10 My invention relates specifically to improved features of construction and arrangement of the master bushing 24 adapted to facilitate the separation and subsequent coupling together of the component complementary parts of the bushing. 15 The bushing, illustrated in the embodiment of the invention of Figures 1 to 6 inclusive, comprises complementary sections 26 and 28 hingedly connected by a pintle or hinge pin 30, the parts when closed jointly forming a recess 32 having a downwardly tapered portion 34 for coaction with the conventional slips adapted to engage the drill pipe, the latter being omitted in the interest of clearness. Section 26 of the bushing is provided with spaced lugs 36 and 38 and the section 28 is 20 provided with similar lugs 40 and 42. The lugs 36 to 42 have aligned apertures formed therein to receive the hinge pintle 30 extending therethrough. Different portions along the length of this pin, as illustrated, vary in diameter by small 25 increments, as do the apertures in the lugs, with which these varying portions of the pintle coact. This feature is desirable to facilitate shifting the parts 26 and 28 relatively to one another in the direction of the length of the pintle so as to 30 effect disengagement of the interlocking tooth-like portions to be presently described.

At points approximately diametrically opposite the pintle 30, the complementary sections 26 and 28 are formed with abutting longitudinal walls 40 446—48, 46a—48a and 46b—48b. The section 26 is provided with notched portions 50 and 52 and adjacent upwardly extended teeth 50a and 52a. Similarly, the section 28 is formed with notched portions 54 and 56 and adjacent teeth 54a and 56a, the teeth 50a and 54a overlapping or interlocking adjacent the top of the bushing and the teeth 52a and 56a interlocking near the lower portion of the bushing as clearly shown in Figure 3.

50 As shown in Figure 2, the complementary portions of the bushing are so proportioned and constructed as to provide a clearance space, indicated by the dimension line X in Figure 2, between the lugs 42 and 36 which is a trifle greater than the vertical distance between the bottom of

the notch 50 and the top of the tooth 50a, it being noted that this vertical distance is the same between the bottom of the notch 52 and the top of the tooth 52a.

In order to separate the interlocking connection between the complementary sections 26 and 28 it is merely necessary to shift them in the direction of the length of the pivot pin whereupon the interlocking teeth 50a and 54a and 52a and 56a will be disengaged so as to permit the sections to be swung relatively to one another, for example, to the position as shown in Figure 5. This will permit the ready removal of slips and the drill pipe. The relative longitudinal shifting of the sections 26 and 28 can be conveniently effected by use of an overhead tackle, as shown in Figure 4. To this end I provide recessed portions 58 and 60 so as to permit hooks 59 and 61 to be engaged under pin-like grips 58a and 60a. The hooks 59 and 61 may be located at the lower extremities of chains 62 and 64 which connect to a ring on a chain or cable leading to a suitable overhead hoist. In the tackle of Figure 4 it will be noted that chain 64 is shorter in length than chain 62. As thus arranged, an upward pull on the suspension hook 68 will first shift the section 28 upwardly relatively to the section 26 until the top of lug 42 takes up the clearance space marked X in Figure 2 and then strikes the under side of the lug 36. Thereafter the two parts will move upwardly in unison and since this relative longitudinal upward movement disconnected the interlocking teeth, the parts can be readily separated to the condition of Figure 5.

In Figure 6 I have shown a modification in which the abutting faces of the teeth are adapted to be tapered, as shown by the inclined line of abutment 70. Such tapering of the teeth provides for wedgingly engaging the parts when they are in locked position, which in some cases is desirable.

In the modification of Figures 7 and 8 the complementary sections 26a and 28a are of substantially the same construction as shown in Figures 1 to 5 with the exception that instead of interlocking them by the use of coacting teeth, I provide a plurality of dowel pins 72 fixedly secured in one of the complementary members and making a slip fit with apertures 74 in the other section. The length of the projecting portions of the dowel pins is slightly less than the clearance marked X' in Figure 8 so that when the top face of the lug 42 engages the bottom face of the lug 36, the dowels of one section will clear the apertured portions of the mating section, thus permitting separation of the parts as previously suggested in the construction shown in Figure 5.

It will be noted that the bushing of my invention is automatically interlocked when positioned in the rotary, and therefore maintains a substantially constant tapered recess for the slips irrespective of wear between the bushing and table. Also, upon separation of the interlocking portions of the bushing and upon raising the same from the table, the bushing parts are automatically released for opening movement about the pintle.

While I have described features which are considered highly desirable from the standpoints of construction and practical operation, it is to be understood that substitutions of equivalents may be made by those skilled in the art without departure from the invention as defined in the appended claims.

I claim:

1. A master bushing for the rotary table of an oil-well drilling machine, comprising a pair of generally semicylindrical complementary sections, each section having a pair of hinge lugs with aligned holes drilled therethrough, the lugs of each section interfitting with those of the other, a pintle extending through said holes, the spacing between the lugs of one section being greater than the height of the lug of the other section disposed therebetween to permit said other section to be raised a predetermined distance relative thereto, said sections having interlocking portions on the side opposite said lugs and pintle, said interlocking portions each including a member on one section having a recess open at the top and a downwardly projecting member fixed on the other section and adapted to penetrate said recess when said other section is in lowermost position by a distance less than said predetermined distance, whereby the interlocking portions are fully disengaged when said other section is raised said predetermined distance.

2. A bushing as defined by claim 1 characterized by said interlocking portions having the form of axially extending notches on said one section and teeth on the other effective normally to lock said sections to one another, the axial length of said teeth and notches being slightly less than said predetermined distance.

3. A bushing as defined by claim 2 wherein the abutting faces of the notches and teeth are inclined axially to effect a wedging engagement of the sections.

4. A bushing as defined by claim 1 characterized by said downwardly projecting member being a lug with an axial dowel pin firmly secured thereto, and said recessed member being a lug with a hole therein to receive the projecting end of said dowel pin.

AUGUST R. MAIER.
